(57) **CLAIM**

The ornamental design for a wall hanging bill and appointment organizer, as shown and described.

DESCRIPTION

FIG. 1 is a perspective view showing my new wall hanging bill and appointment organizer;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan elevational view thereof;

FIG. 7 is a bottom plan elevational view thereof; and,

FIG. 8 is a front elevational view showing the same invention with an alternative design in broken lines. The broken lines shown in FIGS. 1, 2 and 8 are for illustrative purposes only and form no part of the claimed design.
